AIR OR GAS DISTRIBUTOR

Jost Sassenberg, Cologne, Germany, assignor to
 Franz J. Kurth, Cologne-Dellbruck, Germany

Application January 9, 1933, Serial No. 650,916,
 and in Germany January 12, 1932

5 Claims. (Cl. 98—40)

This invention relates to a method of and apparatus for introducing air into a room.

Distributors are known for supplying air into a room without the occurrence of draught, the velocity of the air introduced being entirely or partly suppressed immediately after its admission into the room. Under certain atmospheric conditions, however, if the air is supplied as is generally desirable in a draught-free manner it may not add to the comfort of the occupants of the room, for instance on sultry summer days, in vehicles or on board ship (for example in passenger cabins, saloons or offices) and in tropical climates. In these cases air introduced with more or less high velocity may be found pleasing.

One object of the invention is to provide means whereby it is possible to supply a current of air to a room either without any appreciable velocity, that is to say, free from draught, or with a velocity of flow, that is to say, with the desired draught.

The invention is concerned with a method of introducing air into a room by causing an air current issuing from an air conduit to pass through an air distributor which is located in front of the outlet end of said conduit, said distributor being of the type comprising a number of throughway passages which increase in cross-sectional area from their inlet to their outlet ends. According to the present invention, the velocity of the air entering the room can be varied by an angular adjustment of the air distributor and the outlet of the inlet conduit relatively to one another.

The invention also includes apparatus for the purpose set forth and comprising an air distributor of the type described adapted to be arranged in front of the outlet end of an inlet conduit, wherein the air distributor is adjustable angularly relatively to the outlet end of the inlet conduit.

According to one feature of the invention a channel is provided connecting the inlet conduit and the air distributor and so arranged that all of the air issuing from the inlet conduit is directed into the air distributor in any position of the latter relatively to the inlet conduit.

According to another feature of the invention, the air inlet conduit communicates with the air distributor through a chamber formed by two spherical parts one rotatable within the other. One of these parts is connected to the inlet conduit and the other to the air distributor, thus permitting the inlet conduit and the air distributor to be angularly adjusted relative to one an-

other. It will be appreciated that this chamber constitutes the channel aforesaid.

Preferably, one of the said spherical parts is fixed to an annular plate surrounding the outlet end of the inlet conduit while the other spherical part carries the air distributor and has an outlet aperture which registers with the inlet aperture of the air distributor.

One embodiment of the invention will now be described with reference to the accompanying drawings on which:

Figure 1 shows the apparatus in vertical section with the air distributor arranged with its axis in alignment with that of the air inlet conduit,

Figure 2 is a similar view showing the air distributor angularly displaced,

Figure 3 is a view of a modification of the air distributor drawn to a larger scale, and

Figure 4 is an underside view of the innermost 75 conical partition of the construction shown in Figure 3.

The drawings are diagrammatic and like reference characters indicate like parts throughout.

As shown in Figures 1 and 2, the air distributor L comprises an annulus t^1 and five funnel-like members t^2 — t^6 arranged one within another to provide a number of throughway passages which increase in area from their inlet to their outlet ends. The annulus t^1 is secured at k to a flange on a hollow spherical part f which is rotatably mounted in a hollow spherical socket formed by the spherical parts d and e . A flange on the part e is bolted at i to a flange on the lower end of a conical tubular support c , and a flange on the upper end of said support is bolted at h to an annular plate b which surrounds the inlet conduit a to which it is welded, soldered or otherwise secured. The spherical part d has at its upper end a flange which is bolted at g to the annular plate b . The spherical part f may be retained in the spherical parts d — e , so that it can be readily rotated therein by any convenient means, and any suitable means may be provided for holding the part f in different positions of adjustment relative to the parts d and e .

Since an air current issuing from a conduit flows out in a conical stream the periphery of which makes an angle of about 15° with the bounding wall of the conduit, the air current issuing from the inlet conduit a flows out approximately in a conical stream bounded by the dotted lines n — o and p — q . The diameter of the air current as it enters the air distributor is o — q , and the outlet aperture of the spherical part f 110

and of the inlet aperture in the annulus t^1 are approximately of the same diameter.

The annulus t^1 carries on one side a bar s with a button m to enable the air distributor L and the spherical part f to be rotated conveniently in any direction.

When the air distributor L occupies the position shown in Figure 1 with its axis in alignment with that of the inlet conduit a , the air current 10 as it enters the distributor is divided into a number of separate currents which issue from the air distributor in all directions with a reduced velocity of flow. This position of the air distributor may be indicated by suitable marks on the spherical part f , and if desired also on the spherical part e .

If the air distributor L is displaced as shown in Figure 2, some of the throughway passages therein will be out of the path of the air current 20 issuing from the inlet conduit a . In the example shown, no air will flow through the passages between the annulus t^1 and the funnel-like member t^2 and between the funnel-like members t^2 , t^3 , on the left-hand side of the distributor as seen 25 in Figure 2 because the inlets to those passages are outside the lateral bounding wall $n-o$ of the air current. On the opposite side of the distributor, the corresponding throughway passages are likewise inoperative, because the lateral bounding 30 wall $p-q$, of the air current meets the spherical part f at q . The air current after it meets the spherical part f continues to flow for some distance in a path of the same curvature as said spherical part and thus sweeps past the inlets to 35 the throughway passages aforesaid. The whole air current is thus constrained to pass through the funnel-like members t^3-t^6 where it meets with little resistance and issues from the distributor with a perceptible velocity of flow with the 40 result that the air entering the room is again perceived as a draught.

It may sometimes be desirable for the velocity of the flow of the air issuing from the air distributor to be perceptible at a distance of from three 45 to four metres from the distributor. In such cases, it is preferable that the innermost funnel-like member shall be of such a size that air can flow through this member without appreciable loss of velocity. In order, however, to ensure a draught-free distribution of air in the 50 normal position of the air distributor, that is when its axis is in alignment with that of the air inlet conduit, there may be provided according to a further feature of the invention a valve controlling that funnel-like member, which valve is arranged to close said funnel-like member when the air distributor is in its normal position, but is automatically opened when the air distributor 55 is displaced angularly. A convenient valve for this purpose is shown in Figures 3 and 4. In this construction the innermost funnel-like member t^6 of Figures 1 and 2 is omitted so that the larger funnel-like member t^5 is now innermost. Mounted in the inner end of this funnel-like 60 member is a disc u which is fixed to a spindle v rotatable in bearings w in the wall of said funnel-like member. This disc, if desired may be arranged at any other position in the funnel-like member. When the air distributor L is in its 65 normal position as shown in Figure 3, the pressure of the air issuing from the inlet conduit a is evenly distributed over said disc which is thereby maintained horizontal and prevents the air from passing through the funnel-like member 70 t^5 . When the air distributor is displaced angularly 75

the disc u due to the uneven distribution of air pressure on its surface tilts into the position shown at u^1 in Figure 3 and permits air to pass through the funnel-like member t^5 .

The invention is not restricted to the precise constructional details described. For instance, the valve u instead of being controlled by the air current may be operated mechanically but automatically, when the air distributor is adjusted, by providing a suitable arrangement of links between the valve and the spherical part d .

Having fully described my invention, what I claim as new, and desire to secure by Letters Patent, is—

1. Air or gas distributing means comprising, in combination, an air or gas supply conduit, an air or gas distributor comprising a series of successively larger outwardly flaring truncated hollow formations open at their ends and disposed to provide a series of air or gas passages therebetween, the smaller open ends of said formations all facing the inner end of the distributor, the inner edges of said formations being spaced apart laterally with respect to the axis of the distributor, a hollow truncated spherical member substantially directly affixed at its outer end to the formation defining the inner end of the distributor, said member having an opening in its outer end alined with and of a diameter at least as great as the opening in the inner end of the formation defining the inner end of the distributor, said member having an opening in its inner end of greater diameter than the discharge end of the conduit, said member between its ends being of greater diameter than the opening in the outer end thereof, and a second truncated spherical member cooperating with first said spherical member to mount the distributor for universal pivotal adjustment in front of the conduit and to provide an air or gas passageway between the inner end of the distributor and the conduit, said second mentioned truncated spherical member also being of greater diameter between its ends than the opening in the outer end of the first mentioned truncated spherical member.

2. In combination, an air or gas distributor comprising a series of successively larger outwardly flaring truncated hollow formations open at their ends and disposed to provide a series of air or gas passages therebetween, the smaller open ends of said formations all facing the inner end of the distributor, the inner edges of said formations being spaced apart laterally with respect to the axis of the distributor, a hollow truncated spherical member substantially directly affixed at its outer end to the formation defining the inner end of the distributor, said member having an opening in its outer end alined with and of a diameter at least as great as the opening in the inner end of the formation defining the inner end of the distributor, a second truncated spherical member to be fixedly mounted and embracing the first mentioned truncated spherical member to mount the distributor for universal pivotal adjustment, said second mentioned truncated spherical member having an air or gas inlet opening in its inner end, said first mentioned truncated spherical member having an opening in its inner end of greater diameter than the opening in the inner end of said second mentioned member, and said first mentioned spherical member being of greater diameter between its ends than the opening in the outer end thereof.

3. An air or gas distributing means comprising, in combination, an air or gas supply conduit,

- an air or gas distributor comprising a series of successively larger outwardly flaring truncated hollow formations open at their ends and disposed in spaced relationship with their axes disposed substantially in the same straight line to provide a series of air or gas passages therebetween, the smaller open ends of said formations all facing the inner end of the distributor, the inner edges of said formations being spaced apart laterally with respect to the substantially common axis of said formations, a hollow truncated spherical member substantially directly affixed at its outer end to the formation defining the inner end of the distributor, said member having an opening in its outer end aligned with and of a diameter at least as great as the opening in the inner end of the member defining the inner end of the distributor, said member having an opening in its inner end of greater diameter than the discharge end of the conduit, said member between its ends being of greater diameter than the opening in the outer end thereof, and a second truncated spherical member embracing said first mentioned spherical member, said second member being fixedly secured in advance of the outlet end of the conduit so as to support the distributor for universal pivotal adjustment relative to the conduit, the common center of the truncated spherical members being disposed in prolongations of the axes of the conduit and the distributor.
4. In combination, an air or gas distributor comprising a series of nested outwardly flaring truncated hollow formations open at their ends and disposed to provide a series of air or gas passages therebetween, the smaller ends of said formations all facing the inner end of the distributor and being of progressively increasing diameter from the innermost formation outwardly, means to mount said distributor with its inner end in air or gas receiving relationship to the discharge end of a conduit and for pivotal adjustment relative to such conduit, and a free swinging pivoted valve disk within the innermost hollow formation. 80
5. In combination, an air or gas distributor comprising a series of nested outwardly flaring truncated hollow formations open at their ends and disposed to provide a series of air or gas passages therebetween, the smaller ends of said formations all facing the inner end of the distributor and being of progressively increasing diameter from the innermost formation outwardly, means to mount said distributor with its inner end in air or gas receiving relationship to the discharge end of a conduit and for pivotal adjustment relative to such conduit, and a pivoted free swinging balanced valve disk within the inner end portion of the innermost hollow formation. 85
